DEEP WELL DRILL

Filed Oct. 10, 1932

FIG 1.

FIG 2.

FIG 3.

Russell GieseY
INVENTOR.

BY

J. Vincent Martin

ATTORNEY.

UNITED STATES PATENT OFFICE

RUSSELL GIESEY, OF OKLAHOMA CITY, OKLAHOMA, ASSIGNOR TO REED ROLLER BIT COMPANY, OF HOUSTON, TEXAS, A CORPORATION OF TEXAS

DEEP WELL DRILL

Application filed October 10, 1932. Serial No. 637,018.

This invention relates to deep well drills. The drill stem employed in deep well drilling comprises a pipe made in sections and having on its lower end a drill bit. A long 5 drill stem is very heavy and for reasons well known to those skilled in the art it must be removed from and then again lowered into the well at certain intervals as the drilling proceeds. To reduce the strain on the hoisting apparatus when the drill pipe is lowered into the well a valve, known as a float valve, is mounted in the drill stem to prevent the passage of water in the well upwardly therethrough, whereby a portion of 10 the weight of the drill stem is placed upon the water in the well. This invention has for one of its objects the provision of a new and improved float valve of this type.

Conventional deep well core drills comprise a drill stem having a bit secured to the lower end thereof and having a central opening, and a core barrel within the stem to receive and retain the core of the formation entering through said opening. In the upper 25 end of the core barrel is a relief valve serving to permit the escape from the barrel of fluid that would otherwise be confined therein and to prevent the passage from the interior of the drill stem into the barrel of 30 muddy water known as slush. It is desirable to wash out the core barrel after the drill stem has been lowered into the well and before drilling is commenced by pumping slush downwardly through the drill stem 35 and core barrel, but this cannot be done with the conventional core drill because the relief valve will not permit the slush to enter the core barrel. This invention has for another of its objects the provision of a core drill 40 embodying new and improved means whereby the relief valve will be held away from its seat so that slush may be pumped downwardly through the drill stem and core barrel to wash out the latter, and then released, 45 to perform its usual function during drilling operations.

A further object is to provide in a core drill a new and improved combination of parts, including a float valve and a relief 50 valve.

Other objects will hereinafter appear.

The preferred embodiment of the invention is illustrated by the accompanying drawing wherein Fig. 1 is a partly sectional elevation of the drill; Fig. 2, an enlarged fragmentary sectional view, showing the positions of the parts when slush is being pumped through the core barrel; and Fig. 3, a view similar to Fig. 2 and illustrating the positions of the parts during drilling.

In the drawing the drill stem is indicated at 1. It has secured on its lower end a bit 2 having a central opening 3. Within the drill stem 1 is a core barrel 4 to receive and retain a core of the formation entering 60 through the opening 3. Any conventional core catcher may, if desired, be placed in the opening 3 or in the lower end of this core barrel 4. In the upper end of the core barrel is a flared opening 5, adapted to receive 65 the relief valve 6. The core barrel 4 is substantially concentric with and spaced from the drill stem 1 so that slush pumped downwardly in the drill stem may pass through the space between the core barrel 4 and drill 70 stem 1 and finally out of the slush passageways 7 in the bit.

Above the core barrel is a valve guide 8 in which the stem 9 of the float valve 10 is vertically reciprocable. When the valve 80 10 is upon its seat 11, fluid cannot pass upwardly in the drill stem. Surrounding the stem 9 and bearing upon the guide 8 and the cap 12 carried by the valve stem is a spring 13 which serves to yieldably hold the valve 85 10 closed.

The relief valve 6 is releasably held in the float valve 10 by the radially expandable ring 14. Within the valve stem 9 is a relief valve 90 releasing pin 15 normally held in its inactive position by the spring 16 which bears downwardly against the end wall of the stem 9 and upwardly against the abutment 17 fixed on the pin 15.

The pin actuator is indicated at 18 in Fig. 95 3. It comprises an elongated body substantially X-shaped in cross-section and having a head 18-a.

The drill is used as follows:

When the drill is lowered into the well the 100

5 float valve 10 will prevent the passage of water or other fluid in the well upwardly into the drill stem so that there will be no fluid in the pipe in the drill stem 1 above the float valve 10. A portion of the weight of the drill stem is thereby placed upon the fluid in the well.

10 After the drill stem has been lowered to the bottom of the well, or to any predetermined point, slush may be pumped downwardly in the drill stem. Overcoming the resistance of the spring 13 and the pressure of the fluid below the float valve 10, the slush will open the valve 10 and pass downwardly through 15 the opening 5 and into the core barrel 4. After the core barrel has been washed out by the slush passing therethrough, the driller may then drop into the drill stem the pin actuator 18. The actuator 18, moving downwardly in the drill stem, will strike the pin 15 and move it downwardly against the resistance of spring 16 to force the relief valve 6 out of the float valve 10 against the resistance of ring 14. The relief valve 6 will then 20 upon fall into the opening 5 to close it. The drill stem may then be rotated to penetrate the formation. The relief valve 6 will then 25 perform its usual function; that is, it will serve to prevent the entrance of slush into 30 the core barrel 4 through the opening 5 and will permit the escape from the core barrel of fluid that would otherwise be confined therein.

35 The invention is not limited to the preferred embodiment herein disclosed. Various changes may be made within the scope of the following claims.

I claim:

40 1. A drill having a stem; a bit to which fluid may be pumped through said stem; a core barrel in said stem and having an open flared upper end communicating with the interior of said stem; a valve guiding member in said stem above said core barrel; a float 45 valve having a stem movable in said member; a spring surrounding said valve stem and serving to yieldably hold said float valve closed; a relief valve releasably secured to said float valve; a relief valve releasing pin 50 movable in said valve stem; a spring surrounding said pin and serving to yieldably hold said pin in its inactive position; and a pin actuator movable downwardly in said stem to move said pin into its active position to permit movement of said relief valve into 55 said opening.

60 2. A drill having a stem; a bit to which fluid may be pumped through said stem; a core barrel in said stem and having an opening in its upper end communicating with the interior of said stem; a float valve in said stem above said core barrel; a spring to yieldably hold said float valve closed; a relief 65 valve releasably secured to said float valve; a relief valve releasing pin movable in said

float valve; a spring to yieldably hold said pin in its inactive position; and a pin actuator movable downwardly in said stem to move said pin into its active position to permit movement of said relief valve into said opening. 70

3. A drill having a stem; a bit to which fluid may be pumped through said stem; a core barrel in said stem and having an opening communicating with the interior of said stem; a float valve in said stem above said opening; a relief valve releasably secured to said float valve; a relief valve releasing pin movable in said float valve; and a pin actuator movable downwardly in said stem to move said pin into its active position to permit movement of said relief valve into said opening. 75

4. A drill having a stem; a bit to which fluid may be pumped through said stem; a core barrel in said stem and having an opening communicating with the interior of said stem; a float valve in said stem above said opening; a relief valve releasably secured to said float valve; and means to release said relief valve to permit movement thereof into 80 said opening. 85

5. A drill having a stem; a bit to which fluid may be pumped through said stem; a core barrel in said stem and having an opening communicating with the interior of said stem; a relief valve; means to releasably hold said valve away from said opening to permit fluid to be pumped from said stem through said barrel; said means serving to 95 so hold said valve independently of the pressure of said fluid; and means to release said valve to permit movement thereof into said opening. 100

6. A drill having a stem; a bit to which fluid may be pumped through said stem; a core barrel in said stem and having an opening communicating with the interior of said stem; a relief valve; an element in said stem to releasably hold said valve away from said opening to permit fluid to be pumped from said stem through said barrel; and an actuator movable downwardly in said stem to cause said element to release said valve to 110 permit movement thereof into said opening. 115

7. A drill having a stem; a bit to which fluid may be pumped through said stem; a core barrel in said stem and having an opening communicating with the interior of said stem; a relief valve; an element in said stem to releasably hold said valve away from said opening; said element including a valve releasing pin; and a pin actuator movable downwardly in said stem to move said pin into its active position to permit movement of said valve into said opening. 120 125

In testimony whereof, I hereunto affix my signature.

RUSSELL GIESEY.
